(57) **CLAIM**

The ornamental design for a hair weaving tool, as shown and described.

DESCRIPTION

FIG. 1 is a top front perspective view of the hair weaving tool showing my new design;

FIG. 2 is a front elevation view thereof;

FIG. 3 is a rear elevation view thereof;

FIG. 4 is a top plan view thereof;

FIG. 5 is a bottom plan view thereof;

FIG. 6 is a right elevation view thereof, with the left elevation view being a mirror image thereof; and,

FIG. 7 is a perspective view thereof, shown in-use.

The broken lines in FIG. 7 showing the hair weaving tool in use illustrates environment and forms no part of the claim.
